[57] ABSTRACT

N,N-dialkylamidoximes and their derivatives are biologically active compounds possessing exceptional herbicidal activity. These compounds can be characterized by the following structural formula:

in which R can be hydrogen, C₁—C₆ alkyl, C₃—C₆ cycloalkyl, C₁—C₆ monoalkyl or C₂—C₆ dialkyl carbamoyl, C₆—C₁₀ aryl carbamoyl, C₁—C₆ mono- or C₂—C₆ dialkyl or C₆—C₁₀ aryl thiocarbamoyl, C₆—C₁₀ aryl, C₁—C₆ acyl, C₁—C₆ alkylsulfonyl, C₆—C₁₀ arylsulfonyl, or a phosphorus-containing moiety defined below; wherein R₅ is a C₁—C₆ alkyl, C₂—C₆ alkoxyalkyl, C₂—C₆ alkylthioalkyl, C₁—C₆ haloalkyl, C₆—C₁₀ aryl, C₆—C₁₀ halo-substituted aryl, C₇—C₁₁ arylalkyl and C₇—C₁₁ halo-substituted arylalkyl, C₂—C₆ alkenyl and C₂—C₆ alkynyl; R₁ and R₂ can be the same or different and are C₁—C₆ alkyl or C₃—C₆ cycloalkyl or taken together can form a cyclic ring. Similarly, R₁ and R₂ taken together can form a cyclic ring.

A preferred embodiment of these compounds is characterized by the following structural formula:

R₃ and R₄ can be the same or different and are C₁—C₆ alkyl, C₁—C₆ alkoxy, C₆—C₁₀ aryloxy, C₁—C₆ alkylthio, C₆—C₁₀ arylthio, C₁—C₆ haloalkyl, C₆—C₁₀ aryl, C₆—C₁₀ halo-substituted aryl, C₇—C₁₁ arylalkyl and C₇—C₁₁ halo-substituted arylalkyl; C₂—C₆ alkenyl and C₂—C₆ alkynyl; X is either O or S. In a preferred embodiment, when R₅ is limited to C₆—C₁₀ aryl, the phosphorylated compounds have been shown to possess an exceptionally good herbicidal activity.

13 Claims, No Drawings

N,N-DIALKYLAMIDOXIME PHOSPHATES

This invention relates to novel N,N-dialkylamidoximes and their derivatives. In one aspect, this invention relates to N,N-dialkylamidoxime phosphate esters. In another aspect, this invention relates to N,N-dialkylarylamidoxime phosphate esters. In another aspect, this invention relates to the use of these novel N,N-dialkylamide and arylamidoxime phosphate esters as herbicides.

It is an object of the present invention to provide new thiophosphoric and phosphoric N,N-dialkylamidoxime phosphate esters which possess improved herbicidal activity.

It is another object of the subject invention to provide a novel herbicidal use for said compound. Other objects and many of the attendant advantages of this invention will be readily appreciated as the same becomes better understood, by reference to the following detailed description.

The compounds falling within the scope of this invention are characterized by the following structural formula:

25

in which R can be hydrogen, C₁—C₆ alkyl or C₃—C₆ cycloalkyl, C₁—C₆ mono- or C₂—C₆ dialkyl carbamoyl, C₆—C₁₀ aryl carbamoyl, C₁—C₆ mono- or C₂—C₆ dialkyl or C₆—C₁₀ aryl thiocarbamoyl, C₆—C₁₀ aryl, C₁—C₆ acyl, C₁—C₆ alkylsulfonyl, C₆—C₁₀ arylsulfonyl, or a phosphorus-containing moiety defined below; wherein R₅ is C₁—C₆ alkyl, C₂—C₆ alkoxyalkyl, C₂—C₆ alkylthioalkyl, C₁—C₆ haloalkyl, C₆—C₁₀ aryl, C₆—C₁₀ halo-substituted aryl, C₇—C₁₁ arylalkyl and C₇—C₁₁ halo-substituted arylalkyl, C₂—C₆ alkenyl, and C₂—C₆ alkynyl; R₁ and R₂ can be the same or different and are C₁—C₆ alkyl or C₃—C₆ cycloalkyl or taken together can form a cyclic ring. Similarly, R₁ and R₅ taken together can form a cyclic ring.

A preferred embodiment of these compounds is characterized by the following structural formula:

50

R₃ and R₄ can be the same or different and are C₁—C₆ alkyl, C₁—C₆ alkoxy, C₆—C₁₀ aryloxy, C₁—C₆ thioalkyl, C₆—C₁₀ thioaryl, C₁—C₆ haloalkyl, C₆—C₁₀ aryl, C₆—C₁₀ halo-substituted aryl, C₇—C₁₁ arylalkyl and C₇—C₁₁ halo-substituted arylalkyl; C₂—C₆ alkenyl and C₂—C₆ alkynyl; X is either O or S.

In a preferred embodiment, when R₅ is limited to C₆—C₁₀ aryl, the phosphorylated compounds have been shown to possess an exceptionally good herbicidal activity.

It has also been found that phosphate esters of N,N-di-alkylarylamidoximes possessed marked herbicidal activity and possess also definite crop selectivity.

The specific examples of the novel compounds covered by this invention are as follows:

Compound

No.

34 0-(1,5-dinitro-4-trifluoromethylphenyl)-N,N-dimethylbenzamidoxime

The compounds falling within the scope of this invention may be prepared via the sequence given below starting with N,N-dimethylbenzamide (commercially available; Fisher Scientific Co.). Step I:

The conditions for this Step are:

	Mol Ratio COCl ² /Amide	Solvent	Temp. °C.	P. Atm.	Contact Time, Hrs.
Broad	1.00-5.00	hydrocarbons, ¹ such as toluene, heptane; chlorinated hydrocarbons, such as chloroform, carbontetrachloride; ethers, such as diethylether, THF	-50° to +100°	1-10.0	10 min. to 100
Preferred	1.00-1.50	chloroform	-10 to +30°	1-1.5	1-50

¹ such as toluene, heptane; chlorinated hydrocarbons, such as chloroform, carbontetrachloride; ethers, such as diethylether, THF

Step II:

The reaction conditions for this Step are:

	Mole NH ₂ OH·HCl/ mol Amide	Mole NaOH/ mol	Organic Solvent	Temp. °C.	P. Atm.	Hours
Broad	1.0	3.0-7.0	A	-50°	1-	0.10- 100
				to +100°	10.0	
Preferred	1.1	3.0-4.0	Chloro- form	-10° to +30°	1-1.5	0.5- 10

⁴ same as those employed in Step I

Step III:

The reaction conditions for this Step are:

	Mole base/ mole oxime	Mole chloro- phosphate/ mole oxime	Solvent	Temp. °C.	P. Atm.	Base
Broad	1.0-1.5	1.0-1.5	hydro- carbons	0°-100° (¹)	1-10	1) alkali metals
Preferred	1.0- such as benzene, toluene, heptane ethers, such as diethyl ether, THF, Dioxane	1.0-1.1	tetrahy- drofuran	0°-100°	1-1.5	2) metal alkyls 3) metal amides sodium

The compounds of the invention have general herbicidal properties. They are especially useful in certain types of weed control such as, for example, in application to crop lands to give control of the common weeds, without harming the crop plants; and for the control of crabgrass in lawns.

Herbicidal compositions of the invention are prepared by admixing one or more of the active ingredients defined heretofore, in herbicidally effective amounts with a conditioning agent of the kind used and referred to in the art as a pest control adjuvant or modifier to provide formulations adapted for ready and efficient application to soil or weeds (i.e., unwanted plants) using conventional applicator equipment.

Thus, the herbicidal compositions or formulations are prepared in the form of solids or liquids. Solid compositions are preferably in the form of granulars or dusts.

The compositions can be compounded to give homogeneous free-flowing dusts by admixing the active compound or compounds with finely divided solids preferably talc, natural clays, pyrophyllite, diatomaceous earth, or flours such as walnut shell, wheat, redwood, soya bean, and cotton-seed flours. Other inert solid conditioning agents or carriers of the kind conventionally employed in preparing pest control compositions in powdered form can be used.

Granulars can be compounded by absorbing the compound in liquid form onto a preformed granular diluent. Such diluents as natural clays, pyrophyllite, diatomaceous earth, flours such as walnut shell, as well as granular sand can be employed.

In addition, granulars can also be compounded by ad-mixing the active ingredient with one of the powdered diluents described hereinabove, followed by the step of either pelleting or extruding the mixture.

Liquid compositions of the invention are prepared in the usual way by admixing one or more of the active ingredients with a suitable liquid diluent medium. In the cases where the compounds are liquids, they may be sprayed in ultra low volume as such. With certain solvents, such as alkylated naphthalene or other aromatic petroleum solvents, dimethyl formamide, cyclic ketones, relatively high up to about 50 percent by weight or more concentration of the active ingredient can be obtained in solution.

The herbicidal compositions of the invention whether in the form of dusts or liquids, preferably also include a surface-active agent sometimes referred to in the art as a wetting, dispersing, or emulsifying agent. These agents, which will be referred to hereinafter more simply as surface-active dispersing agents, cause the compositions to be easily dispersed in water to give aqueous sprays which, for the most part, constitute a desirable composition for application.

The surface-active dispersing agents employed can be of the anionic, cationic, or nonionic type and include, for example, sodium and potassium oleate, the amine salts of oleic acid, such as morpholine and dimethylamine oleates, the sulfonated animal and vegetable oils, such as sulfonated fish and castor oils, sulfonated petroleum oils, sulfonated acyclic hydrocarbons, sodium salt of lignin sulfonic acid (goulac), alkyl-naphthalene sodium sulfonate, sodium salts of sulfonated condensation products of naphthalene and for-

malde-hyde, sodium lauryl sulfate, disodium monolauryl phosphate, sorbitol laurate, pentaerythritol monostearate, glycerol monostearate, diglycol oleate, polyethylene oxides, ethylene oxide condensation products with stearyl alcohol and alkyl-phenol, polyvinyl alcohols, salts, such as the acetate of polyamines from reductive amination of ethylene-carbon monoxide polymers, laurylamine hydrochloride, lauryl-pyridinium bromide, stearyl trimethylammonium bromide, cetyltrimethylbenzyl ammonium chloride, lauryl-dimethylamine oxide, and the like. Generally, the surface-active agent will not comprise more than about 5 to 15 percent by weight of the composition, and in certain compositions the percentage will be 1 percent or less. Usually, the minimum lower concentration will be 0.1 percent.

The herbicidal compositions are applied either as a spray, granular or a dust to the locus or area to be protected from undesirable plant growth, commonly called weeds, i.e. plants growing where they are not wanted. Such application can be made directly upon the locus or area and the weeds thereon during the period of weed infestation in order to destroy the weeds, or alternatively, the application is made in advance of an anticipated weed infestation to prevent such infestation. Thus, the compositions can be applied as aqueous foliar sprays but can also be applied as sprays directly to the surface of the soil. Alternatively, the dry powdered compositions can be dusted directly on the plants or on the soil.

In applying the herbicidal compositions of the invention for selective weed control as in the control of weeds in cotton or corn fields, the compositions are preferably applied after emergence of the seedlings. In other words, the applications are of the post-emergence type although preemergence applications may also be effective.

The active compound is, of course, applied in an amount sufficient to exert the desired herbicidal action. The amount of the active compound present in the compositions as actually applied for destroying or preventing weeds will vary with the manner of application, the particular weeds for which control is sought, the purpose for which the application is being made, and like variables. In general, the herbicidal compositions as applied in the form of a spray, dust or granular, will contain from about 0.1 to 100 percent by weight of the active compound.

Fertilizer materials, other herbicidal agents, and other pest control agents such as insecticides and fungicides can be included in the herbicidal compositions of the invention if desired.

The term "carrier" or "diluent" as used herein means a material, which can be inorganic or organic and synthetic or of natural origin, with which the active ingredient is mixed or formulated to facilitate its storage, transport, and handling and application to the plants to be treated. The carrier is preferably biologically and chemically inert and, as used, can be a solid or fluid. When solid carriers are used, they are preferably particulate, granular, or pelleted; however, other shapes and sizes of solid carrier can be employed as well. Such preferable solid carriers can be natural occurring minerals although subsequently subjected to grinding, sieving, purification, and/or other treatments

— including, for example, gypsum; tripolite; diatomaceous earth; mineral silicates such as mica, vermiculite, talc, and pyrophyllite; clays of the montmorillonite, kaolinite, or attapulgite groups; calcium or magnesium limes, or calcite and dolomite; etc. Carriers produced synthetically, as for example, synthetic hydrated silica oxides and synthetic calcium silicates can also be used, and many proprietary products of this type are available commercially. The carrier can also be an elemental substance such as sulfur or carbon, preferably an activated carbon. If the carrier possesses intrinsic catalytic activity such that it would decompose the active ingredient, it is advantageous to incorporate a stabilizing agent, as for example, polyglycols such as diethylene glycol, to neutralize this activity and thereby prevent possible decomposition of the derivatives of the present invention.

For some purposes, a resinous or waxy carrier can be used, preferably one which is solvent soluble or thermoplastic, including fusible. Examples of such carriers are natural or synthetic resins such as a coumarone resin, rosin, copal, shellac, dammar, polyvinyl chloride, styrene polymers and copolymers, a solid grade of polychlorophenol such as is available under the registered trademark "Aroclor," a bitumen, an asphaltite, a wax for example, beeswax or a mineral wax such as paraffin wax or montan wax, or a chlorinated mineral wax, or a microcrystalline wax such as those available under the registered trademark "Mikrovan Wax." Compositions comprising such resinous or waxy carriers are preferably in granular or pelleted form.

Fluid carriers can be liquids, as for example, water or an organic fluid, including a liquefied normally vaporous or gaseous material, or a vaporous or gaseous material, and can be solvents or nonsolvents for the active material. For example, the horticultural petroleum spray oils boiling in the range of from about 275° to about 575° F., or boiling in the range of about 575° to about 1,000° F. and having an unsulfonatable residue of at least about 75 percent and preferably of at least about 90 percent, or mixtures of these two types of oil, are particularly suitable liquid carriers.

The carrier can be mixed or formulated with the active material during its manufacture or at any stage subsequently. The carrier can be mixed or formulated with the active material in any proportion depending on the nature of the carrier. One or more carriers, moreover, can be used in combination.

The compositions of this invention can be concentrates, suitable for storage or transport and containing, for example, from about 5 to about 90 percent by weight of the active ingredient, preferably from about 20 to about 80 wt. percent. These concentrates can be diluted with the same or different carrier to a concentration suitable for application. The compositions of this invention may also be dilute compositions suitable for application. In general, concentrations of about 0.1 to about 10 percent by weight, of active material based on the total weight of the composition are satisfactory, although lower and higher concentrations can be applied if necessary.

The compositions of this invention can also be formulated as dusts. These comprise an intimate admixture of the active ingredient and a finely powdered

solid carrier such as aforescribed. The powdered carriers can be oil-treated to improve adhesion to the surface to which they are applied. These dusts can be concentrates, in which case a highly sorptive carrier is preferably used. These require dilution with the same or a different finely powdered carrier, which can be of lower sorptive capacity, to a concentration suitable for application.

The compositions of the invention can be formulated as wettable powders comprising a major proportion of the active ingredient mixed with a dispersing, i.e., deflocculating or suspending agent, and if desired, a finely divided solid carrier and/or a wetting agent. The active ingredient can be in particulate form or adsorbed on the carrier and preferably constitutes at least about 10 percent, more preferably at least about 25 percent, by weight of the composition. The concentration of the dispersing agent should in general be between about 0.5 and about 5 percent by weight of the total composition, although larger or smaller amounts can be used if desired.

The dispersing agent used in the composition of this invention can be any substance having definite dispersing, i.e., deflocculating or suspending, properties as distinct from wetting properties, although these substances can also possess wetting properties as well.

The dispersant or dispersing agent used can be protective colloids such as gelatin, glue, casein, gums, or a synthetic polymeric material such as polyvinyl alcohol and methyl cellulose. Preferably, however, the dispersants or dispersing agents used are sodium or calcium salts of high molecular weight sulfonic acids, as for example, the sodium or calcium salts of lignin sulfonic acids derived from sulfite cellulose waste liquors. The calcium or sodium salts of condensed aryl sulfonic acid, for example, the products known as "Tanol 731," are also suitable.

The wetting agents used can be nonionic type surfactants, as for example, the condensation products of fatty acids containing at least 12, preferably 16 to 20, carbon atoms in the molecule, or abietic acid or naphthenic acid obtained in the refining of petroleum lubricating oil fractions with alkylene oxides such as ethylene oxide or propylene oxide, or with both ethylene oxide and propylene oxide, as for example, the condensation product of oleic acid and ethylene oxide containing about 6 to 15 ethylene oxide units in the molecule. Other nonionic wetting agents like polyalkylene oxide polymers, commercially known as "Pluronics" can be used. Partial esters of the above acids with polyhydric alcohols such as glycerol, polyglycerol, sorbitol, or mannitol can also be used.

Suitable anionic wetting agents include the alkali metal salts, preferably sodium salts, of sulfuric acid esters or sulfonic acids containing at least 10 carbon atoms in a molecule, for example, the sodium secondary alkyl sulfates, dialkyl sodium sulfosuccinate available under the registered trademark "Teepol," sodium salts of sulfonated castor oil, sodium dodecyl benzene sulfonate.

Granulated or pelleted compositions comprising a suitable carrier having the active ingredient incorporated therein are also included in this invention. These can be prepared by impregnating a granular carrier with a solution of the inert ingredient or by granu-

lating a mixture of a finely divided solid carrier and the active ingredient. The carrier used can consist of or contain a fertilizer or fertilizer mixture, as for example, a superphosphate.

The compositions of this invention can also be formulated as solutions of the active ingredient in an organic solvent or mixture of solvents, such as for example, alcohols; ketones, especially acetone; ethers; hydrocarbons; etc.

Where the toxicant itself is a liquid these materials can be sprayed on crops without further dilution.

Petroleum hydrocarbon fractions used as solvents should preferably have a flash point above 73° F., an example of this being a refined aromatic extract of kerosene. Auxiliary solvents such as alcohols, ketones, and polyalkylene glycol ethers and esters can be used in conjunction with these petroleum solvents.

Compositions of the present invention can also be formulated as emulsifiable concentrates which are concentrated solutions or dispersion of the active ingredient in an organic liquid, preferably a water-insoluble organic liquid, containing an added emulsifying agent. These concentrates can also contain a proportion of water, for example, up to about 50 percent by volume, based on the total composition, to facilitate subsequent dilution with water. Suitable organic liquids include, e.g., the above petroleum hydrocarbon fractions previously described.

The emulsifying agent can be of the type producing water-in-oil type emulsions which are suitable for application by low volume spraying, or an emulsifier of the type producing oil-in-water emulsions can be used, producing concentrates which can be diluted with relatively large volumes of water for application by high volume spraying or relatively small volumes of water for low volume spraying. In such emulsions, the active ingredient is preferably in a nonaqueous phase.

The present invention is further illustrated in greater detail by the following examples, but it is to be understood that the present invention in its broadest aspects, is not necessarily limited in terms of the reactants, or specific temperatures, residence times, separation techniques and other process conditions, etc.; or dosage level, exposure times, test plants used, etc., by which the compounds and/or compositions described and claimed are prepared and/or used.

EXAMPLE 1

Preparation of N,N-Dimethylbenzamidoxime

1.2 moles of phosgene was bubbled into 500 ml of chloroform and cooled to 0° C. via a dry-ice/acetone bath. To the stirred phosgene solution at 10°-15° C. was added dropwise a solution of 180 gms (1.2 moles) of N,N-dimethylbenzamide carried in 50 ml of chloroform. Carbon dioxide evolution was evident. After completing the addition, the solution was warmed to 25° C. and stirred overnight.

A solution of 1.8 moles of hydroxylamine hydrochloride and 1.8 moles of sodium hydroxide contained in 600 ml of water was prepared and cooled to a temperature of 10°-15° C. To this solution was simultaneously added the chloroform solution prepared hereinabove and 2.6 moles of a 50 percent aqueous sodium hydroxide solution. The mixture was stirred at 25° C. for 2 hours after completion of the addition step.

The chloroform layer was separated and the aqueous phase was extracted twice with small portions of chloroform. The combined organic layers were dried over magnesium sulfate and filtered. The chloroform was removed on a rotary evaporator leaving 340 grams of an oil residue.

The residue was taken up in 250 ml of hot cyclohexane and cooled to 8° to crystallize 44 grams of crude product. After recrystallizing from cyclohexane, 35.4 grams of white crystals were obtained having a melting point of 124° to 127° C.

The structure of the product was confirmed as N,N-dimethylbenzamidoxime by infrared and NMR spectroscopy. Calculated for C₉H₁₂N₂O: C, 65.9 H, 7.31 N, 17.08

Found: C, 66.2 H, 7.39 N, 16.91

By following a procedure entirely analogous to that described hereinabove the following amides have been converted to their oximes. The amides themselves are either commercially available or may be synthesized by known methods, e.g. reaction of an amine with an acyl halide or anhydride. The products of these reactions were all identified by either infrared or NMR spectra and an elemental analysis will be recorded for each compound.

EXAMPLE 2

Preparation of O,O-Diphenyl-O-(N,N-Dimethylbenzamidoximino) phosphate

N,N-dimethylbenzamidoxime obtained in Example 1 (15.2 millimoles) was dissolved in 100 ml of anhydrous tetrahydrofuran. Metallic sodium (15.2 mg-atoms) was added and the mixture was refluxed overnight. The suspension was cooled to a temperature of approximately 10° to 15° C. and 15.2 millimoles of diphenyl chlorophosphate was added dropwise. The solution was stirred overnight at 25° C. Ether (25 ml) was added and the solution was filtered to remove sodium chloride. The filtrate was stripped on a rotary evaporator and 7.0 grams (92 percent) of yellow oil was obtained. The identity of the product was confirmed by IR and NMR spectroscopy.

Using a reaction entirely analogous to the above-described step the following phosphorylated oximes were prepared. Their structures were confirmed by IR and NMR spectroscopy.

Starting Amide	Oxime	Analysis	Theoretical	Found	5	N,N-dimethylbenzamidoxime	Diethylchlorothiophosphate	O,O-Diethyl-O-(N,N-dimethyl-pyrolidoximino) phosphate	yellow oil

Amidoximes substituted at oxygen with N-alkyl or N-aryl carbamoyl moieties may be prepared via condensation of an amidoxime with an appropriate isocyanate as shown for step III-B below:

Step III-B:

R	Product	Identification (IR and NMR spectra)			
		M.P., degrees	Calcd., percent	Found, percent	
		C	H	C	H
<chem>-CH3</chem>	<chem>*C(=NOCNHC3)N</chem>	108-114	57.6	7.15	57.9
<chem>-Cl-C6H4-</chem>	<chem>*C(=NOCNHC6H4-Cl)N</chem>	120-122	60.4	5.03	60.5

EXAMPLE 4

Test for Pre-emergence Herbicidal Activity of These Compounds

Representative compounds from those prepared in the previous examples were evaluated for pre-emergence herbicidal activity. The test procedure employed was as follows:

Two flats seeded with six crops (cotton, soybean, alfalfa, corn, rice and oats) and six weeds (mustard, 65 morning-glory, crabgrass, foxtail, barnyard grass and zinnia) were sprayed with a formulation containing the test chemical at the rate given in Tables IV and V. The

test chemicals were sprayed as acetone solutions or acetone suspensions of very small particle size onto the test plants. Sprayers were calibrated to deliver a certain volume of liquid and the calculated amount of active

ingredient which would give a rate corresponding to the indicated pounds/acre. The flats were then held in the greenhouse and a response rated after 12 days to 16 days. Response was rated by a scale of 0-10. The 0-10 scale is defined as: 0 = no injury; 1-3 = slight injury; 4-6 = moderate injury, plants may die; 7-9 = severe injury, plants will probably die; 10 = all plants dead (complete kill). The results of this test as shown in Table III are indicative that many of these compounds show a high degree of herbicidal activity in many weed species, but may remain highly tolerant of desirable crop species.

EXAMPLE 5

Representative derivatives of the various compounds of this invention were evaluated for post-emergence activity. The test procedure was as follows:

Flats were seeded, as described in the previous example and held until the first true leaves had appeared on all plants which were then sprayed in the same fashion as in the preceding example at a rate corresponding to the indicated pounds per acre. The plant responses were rated 12 to 16 days after treatment on the same scale as described previously. The test results are shown in Table IV.

10

3. A compound according to claim 1, which is 0,0-diethyl-0-(N,N-dimethylmethoxyacetamidoximino) phosphate.

5. A compound according to claim 1, which is 0,0-diethyl-0-(N,N-dimethyl-3-chloropropionamidoximino) phosphate.

5. A compound according to claim 1, which is 0,0-diethyl-0-(N,N-dimethyl- β -naphthamidoximino) phosphate.

6. A compound according to claim 1, which is 0,0-diethyl-0-(N,N-dimethyl-p-toluamidoximino) phosphate.

TABLE III.—PRE-EMERGENCE HERBICIDAL ACTIVITY

Compound	Lb./acre	Barnyard grass	Crab-grass	Yellow foxtail	Zinnia	Mustard	Morning glory
O,O-diethyl-O-(N,N-dimethylbenzamidoximino) thiophosphate	10	4	3	3	8	8	8
O,O-diethyl-O-(N,N-dimethylbenzamidoximino) phosphate	10	10	9	9	9	9	9
O,O-dimethyl-O-(N,N-dimethylbenzamidoximino) thiophosphate	10	2	6	4	6	4	8
O,O-diphenyl-O-(N,N-dimethylbenzamidoximino) phosphate	10	6	9	10	9	10	10
Do	2.5	3	6	9	3	8	9

TABLE IV.—POST-EMERGENCE HERBICIDAL ACTIVITY

Compound	Lb./acre	Barnyard grass	Crab-grass	Yellow foxtail	Zinnia	Mustard	Morning glory
O,O-diethyl-O-(N,N-dimethylbenzamidoximino) thiophosphate	10	9	10	10	10	10	10
O,O-diethyl-O-(N,N-dimethylbenzamidoximino) phosphate	10	10	9	10	10	10	10
O,O-dimethyl-O-(N,N-dimethylbenzamidoximino) thiophosphate	10	9	9	4	10	10	8
O,O-diethyl-O-(N,N-dimethyl-3,4-dichlorobenzamidoximino) thiophosphate	10	10	7	6	7	6	5
O,O-diphenyl-O-(N,N-dimethylbenzamidoximino) phosphate	10	10	10	10	10	10	10
Do	2.5	3	7	6	9	9	7

What is claimed is:

1. A compound of the formula

wherein

each of R_1 and R_2 is $\text{C}_1\text{—C}_6$ alkyl or $\text{C}_3\text{—C}_6$ cycloalkyl,

each of R_3 and R_4 is $\text{C}_1\text{—C}_6$ alkyl, optionally substituted by chlorine, $\text{C}_1\text{—C}_6$ alkoxy, $\text{C}_1\text{—C}_6$ alkylthio, $\text{C}_2\text{—C}_6$ alkenyl, $\text{C}_2\text{—C}_6$ alkynyl, phenyl or phenoxy,

R_5 is $\text{C}_1\text{—C}_6$ alkyl optionally substituted by chlorine, $\text{C}_1\text{—C}_4$ alkoxy or $\text{C}_1\text{—C}_4$ alkylthio; $\text{C}_2\text{—C}_6$ alkenyl; $\text{C}_2\text{—C}_6$ alkynyl; phenyl optionally substituted by chlorine or methyl; or naphthyl, and

X is oxygen or sulfur.

2. A compound according to claim 1, which is 0,0-diethyl-0-(N,N-dimethylacetamidoximino) phosphate.

30 7. A compound according to claim 1, which is 0,0-dimethyl-0-N,N-dimethylbenzamidoximino) thiophosphate.

8. A compound according to claim 1, which is 0,0-diethyl-0-(N,N-dimethylmethacrylamidoximino) phosphate.

35 9. A compound according to claim 1, which is 0,0-diethyl-0-(N,N-dihexylbenzamidoximino) phosphate.

10. A compound according to claim 1, which is 0,0-diphenyl-0-(N,N-dimethylbenzamidoximino) phosphate.

11. A compound according to claim 1, which is S,S-dihexyl-0-(N,N-dimethylbenzamidoximino) trithiophosphate.

12. A compound according to claim 1, which is phenyl-0-phenyl-0-(N,N-dimethylbenzamidoximino) thiophosphate.

13. A compound according to claim 1, which is dipropargyl-0-(N,N-dimethylbenzamidoximino) thiophosphinate.
